UNITED STATES PATENT OFFICE.

ARCHIBALD G. SHEAVER, OF CHICAGO, ILLINOIS, ASSIGNEE TO THE BIGAN SAFETY DEVICES COMPANY, INC., OF NEW YORK, N. Y., A CORPORATION OF NEW YORK.

AUTOMATIC TRAIN-CONTROL SYSTEM CONTINUOUS TYPE WITH TRACK-SIDE ENERGY.

Application filed December 29, 1921. Serial No. 325,758.

This invention relates to induction train control systems, and more particularly to an induction train control system of the continuous type; and has special reference to the provision of a continuous induction system arranged to be connected to and influenced by a block signalling system responsive to "safety", "caution" and "danger" track conditions.

10 Among the more important objects of my present invention are the provision of an induction system of the continuous type operative for producing a plurality of train control effects on a vehicle such as "proceed", "speed restrictive" and "stop" effects in response to corresponding traffic conditions; the provision of a continuous induction system in which are employed cooperative vehicle and roadside inductoriums energized 20 from a roadside source of energy for operating train controlling means in predetermined manners; the further provision of a system of this nature in which a plurality of vehicle energy receiving inductoriums co-operate with a plurality of roadside energy transmitting inductoriums for differently influencing a two element relay operative for producing different effects in the train controlling means; and the provision of an induction system of this type in which the roadside inductoriums are selectively energized and controlled from a block signalling system to produce different relative current characteristics in said inductoriums 30 for effecting the desired operations of the train control means.

To the accomplishment of the foregoing and such other objects as may hereinafter appear, my invention consists in the elements and their relation one to the other, as hereinafter particularly described and sought to be defined in the claims, reference being had to the accompanying drawing which shows a preferred embodiment of my invention, and in which:—

Figure 1 is a diagrammatic view of the track circuits.

Figure 2 is a diagrammatic view of the vehicle carried apparatus and circuits, and

50 Figures 3, 4, and 5 are diagrammatic views showing various methods of connecting capacities with the roadside inductoriums.

Referring now more in detail to the drawings and more particularly to Fig. 1 thereof, 55 there are provided for each track section or

block such as A, B, C, and D, a plurality of energy transmitters comprising a set of inductoriums b' and b'' running throughout the length of such section or block, the blocks being provided, as is well known in the art, by dividing the track rails Z by means of the insulating joints y. For influencing and operating the train controlling mechanism, the inductoriums b' and b'' of a section or block are selectively energized from a roadside source of energy such as the alternating current generator G, and the energization controlled by home and distant relays H and D respectively of the next succeeding block, the construction and arrangement providing for the energization of the inductoriums in response to "safety", "caution" and "danger" roadside conditions.

The home relay H of each block is connected as usual across the rails of the block and is energized in the absence of a vehicle on the said block by the track battery b also connected across the rails of such block. The distant relay D of a given block is energized by a roadside source of energy I and is controlled by the home relay H of the block in advance, the distant relay of said given block being thus made to reflect conditions of the next succeeding block. Thus the circuit for the relay D of block B comprises battery I, conductor 12, coil of relay D, conductor 11, and front contact 32 of relay H of the next succeeding block C.

To selectively energize the inductoriums b' and b'' in response to traffic conditions, the inductorium b' of a block such as B is connected to the generator G through the circuit comprising the generator G, conductors 50, 7 and 6, front contact 41 controlled by distant relay D of block C, conductor 2, coil of the inductorium b' , conductor 1, condenser K, conductor 3, front contact 31 of said relay D, and conductors 4, 5, 8 and 31; and the inductorium b'' of said block B is connected to the generator G through the circuit comprising the conductors 31 and 8, the contact 44 controlled by the home relay H of block C, the conductor 16, the condenser KB, conductor 13, coil of the inductorium b'' , conductor 9, contact 42 of said relay H, and conductors 7 and 50. With this construction it will be seen that if the home and distant relays of the block such as block C are energized, this existing under "safety" track conditions and in the absence

of a train in either blocks C or D, the inductoriums b' and b^2 of block B are energized with currents of a given relative phase. It will be further seen that in the event of "caution" track conditions, as when a train occupies the block D deenergizing the home relay H of said block D, the distant relay D of block C will be deenergized and the contacts 31 and 41 controlled thereby will be actuated to close their back contacts, with the result that the circuit connections to the inductorium b' are reversed and the direction of flow of current to said inductorium b' reversed, the instantaneous polarity of the said current in the inductorium b' differing from that in the inductorium b^2 , the currents in these inductoriums now being altered in phase and being for example 180° out of phase. If the relay H of block C is deenergized in response to "danger" track conditions with a train occupying the said block C, the contacts 42 and 44 controlled by the relay H will be opened, with the result that the inductorium b^2 will be deenergized.

While a certain construction is shown and described in connection with the above arrangement, I do not wish to be confined to this exact arrangement of circuits, the main feature of the invention residing in the fact that there are two inductoriums, one of which furnishes energy for one coil of a two element relay carried on a locomotive, the other which furnishes energy for the other element of the same relay, all as will hereinafter be described.

With regard to the arrangement of capacity in these circuits, I do not wish to be confined to the use of condensers only or to the arrangement of series condensers as shown, as there are other ways of accomplishing this result, such as indicated in Figures 3, 4, and 5, as the condensers may be connected across the main leads to the inductorium in parallel with either winding of the same and in case of a high frequency and a desire to limit the value of the condenser capacity, then the arrangement as indicated in Figures 4 and 5 may be used.

In Fig. 2 the wiring or circuits for the moving vehicle with a portion of the roadside apparatus is shown to clearly indicate the operation of the same. In this figure T' indicates the two track rails with the inductoriums b' and b^2 in any section. The inductorium b^2 is connected to the generator by means of the conductors 7 and 8 through the contacts of relay H' and the inductorium b' is also connected to the generator through the pole changing contacts 31-41 of the distant relay D'. R is a translating device in the form of a two element relay carried on a vehicle consisting of the elements a and b , the former of which is connected by conductors 16 and 17 with the coil of a vehicle energy receiving inductorium 101, while the element b is connected through conductors 14 and 15 with the coil of another vehicle energy receiving inductorium 100, the said vehicle inductoriums 101 and 100 being arranged for respective cooperation with the roadside inductoriums b^2 and b' .

The relay R operates the contacts 24 and 25, and when energized with the currents in the elements a and b in phase, said contacts are actuated to assume and hold the position shown in full lines in the figure, and when energized with currents in the elements a and b differing in phase by 180° , as when there is a reversal of direction of flow of current in the element b , the contacts 24 and 25 are actuated to assume and hold the oblique dotted line position. When the relay R is deenergized, as when the element a or b is deenergized, the contacts 24 and 25 will stand in neutral or vertical dotted line position.

With this construction it will be seen that normally under "safety" track conditions, as when the block ahead and the second block ahead are unoccupied, elements a and b of relay R are energized normally such as with currents of like phase, the inductorium b' inducing current into the inductorium 100, while the inductorium b^2 induces current of like phase into the inductorium 101. Under "caution" track conditions, that is, with the second block ahead occupied, elements a and b will be energized with currents of different, such as opposite phase, due to the reversal of direction of flow of current in the inductorium b' ; and under "danger" track conditions with the block in advance occupied, element a will be deenergized due to the deenergization of inductorium b^2 , the contacts 24 and 25 assuming the normal or full line position, the oblique dotted line position, and the vertical neutral line position under the "safety", "caution" and "danger" track conditions respectively.

The speed controller S is carried by the vehicle and has two circuit contacts so arranged that one contact will be opened at some predetermined medium speed, as some 20 or 30 miles per hour, while the other contact is opened at some low speed, as 8 miles or 10 miles per hour. Assume that contact 32 is the medium speed contact, being opened above the predetermined speed and closed below that speed and assume also that contact 33 is the low speed contact, being opened above another predetermined speed and closed below that speed.

The magnet M controls the air valve, as particularly set forth in my Patent No. 1,411,526 of April 4, 1922, while the relay P is used only in connection with the operation of a train under predetermined low speed, the same being controlled also by the release key L, and is normally deenergized. When the relay P is energized through the

use of the release key, it establishes its own holding circuit, through its stick contact 36. For normal operation the circuits are as shown: magnet M controlling the air valve includes in its circuit, conductor 27, relay contact 24, conductors 23 and 18, battery B, and conductors 20 and 34.

When, however, the second block ahead is occupied so that relay D in the block in advance is deenergized, then relay R has its contacts made in the right oblique position as hereinbefore described, so that the circuit of valve magnet M then comprises conductors 27, 29 and 28, contact 32 of speed controller, conductor 26, contact 24 of relay R, conductors 23 and 18, battery B and conductors 20 and 34. This circuit will be maintained until the train or other obstruction in second block ahead gets out of the way, when automatically the circuits will be returned to their normal positions. If the obstruction in the block ahead persists until the vehicle proceeds to that block, then relay H is found to be open so that inductorium b^2 is deenergized for effecting the deenergization of relay R. In this case upon deenergization of relay R the contacts 23 and 24 assume the neutral or vertical position, in which case magnet M becomes deenergized and it can only be energized again by the operation of release key L. When this is done, a circuit is established including conductors 39 and 40, magnet of relay P, conductor 21, contact 24 of relay R in neutral position, made only when relay R is in de-energized condition, conductors 22 and 18, battery B, conductors 20, 43, and release key L. This energizes relay P and when relay P is energized its contact 36 is closed, establishing a circuit through conductor 45, contact 36 and conductor 38, which is in multiple with the release key circuit just described. Relay P, therefore, remains energized and it will remain energized as long as relay R is in a deenergized condition. When relay P is energized, its contact 37 is also closed. When relay R is deenergized the train must stop or travel at or under the predetermined low speed, in which case contact 33 of speed controller S is closed; therefore, if the vehicle is proceeding at or under the predetermined low speed, electromagnet M of the valve is energized through the following circuit: conductors 29 and 30, contact 33 of speed controller S, conductor 35, contact 37 of relay P, conductor 19, battery B, conductors 20 and 34. Immediately, however, when relay H becomes energized, then relay R becomes energized and valve magnet M becomes energized for either normal or medium speed running, depending upon the position of the pole changing contacts of the relay D, and relay P becomes deenergized.

To explain the operation of this system,

assume a train in block C of Figure 1 and a vehicle equipped with this train control system approaching in block B. Relay H in block C will be deenergized so that there will be no energy in inductorium b^2 of block 70 B, consequently relay R, shown in Figure 2, will be deenergized which will cause magnet M to be deenergized and the air brake on the vehicle will be applied to stop the vehicle. When the vehicle is retarded to the predetermined low speed or if it has stopped, the driver upon operating release key L, and the train may proceed at or under the predetermined low speed. Assume the case of block D being occupied and the moving vehicle passing along the track within the block B. When block D is occupied, control relay D for the next preceding block C will be deenergized. When control relay D of block C is deenergized, its contacts are made in reverse position so that the direction of flow of energy in the inductorium b' of block B relative to the direction of flow of energy in the inductorium b^2 of said block B is reversed, therefore, referring again to Figure 2, the relay R has its contacts made in the right oblique position, in which case contact 32 of the speed controller S is brought into series with magnet M, so that magnet M can only be energized at or below the predetermined speed for which contact 32 is closed, in which case the train may proceed under predetermined medium speed.

While I have shown my device in the preferred form, it will be apparent that many changes and modifications may be made in the structure disclosed, without departing from the spirit of the invention, defined in the following claims.

What I claim as new is:

1. In a continuous inductive train control system, the combination with the track rails subdivided into a plurality of sections or blocks, of roadside mechanism comprising a plurality of parallel inductoriums for each section or block disposed substantially the full length of the block, a roadside source of energy, and roadside means for the plurality of inductoriums of a section operable in response to track conditions for connecting one of the inductoriums in circuit with said source of energy under "safety" track conditions and for disconnecting the same under "danger" track conditions.

2. In a continuous inductive train control system, the combination with the track rails subdivided into a plurality of sections or blocks, of roadside mechanism comprising a plurality of parallel inductoriums for each section or block disposed substantially the full length of the block, a roadside source of energy, and roadside means operable in response to track conditions for changing circuit connections between said inductoriums.

- ums and said source of energy for reversing the direction of flow of current in one inductorium relative to the other and for discontinuing the flow of current in one of said inductoriums under predetermined conditions.
3. In a continuous inductive train control system, the combination with the track rails subdivided into a plurality of sections or blocks, of roadside mechanism comprising a plurality of parallel inductoriums for each section or block disposed substantially the full length of the block, a roadside source of energy, and means operable in response to roadside conditions for reversing circuit connections from said source of energy to one of said inductoriums, and additional means also operable in response to roadside conditions for breaking circuit connections from said source of energy to one of said inductoriums.
4. In a continuous inductive train control system, the combination with the track rails subdivided into a plurality of sections or blocks, of roadside mechanism comprising a plurality of parallel inductoriums for each section or block disposed substantially the full length of the block, a roadside source of energy, and means for connecting the said source of energy to one of said inductoriums operative to reverse circuit connections therebetween.
5. In a continuous inductive train control system, the combination with the track rails subdivided into a plurality of sections or blocks, of roadside mechanism comprising a plurality of parallel inductoriums for each section or block disposed substantially the full length of the block, a roadside source of energy, and means for connecting the source of energy to the inductoriums operative to reverse circuit connections to one of said inductoriums and to break circuit connections to one of said inductoriums, the said means comprising a pole changer and a make and break device.
6. In an induction train control system, the combination with two parallel inductoriums paralleling the trackway, a roadside source of energy for said inductoriums, a home relay and a distant relay, and circuit connections between said source of energy and said inductoriums controlled by said relays.
7. In an induction train control system, the combination with sets of parallel inductoriums paralleling the trackway, a roadside source of energy for said inductoriums, a home relay and a distant relay for each set of inductoriums, the distant relay of one set being controlled by the home relay of another set, and circuit connections between said source of energy and said inductoriums controlled by both said relays of a given set.
8. In an induction train control system, the combination with two parallel inductoriums paralleling the trackway, a roadside source of energy for connecting said source of energy to one of said inductoriums operative for reversing circuit connections therebetween, provisions for connecting said source of energy to the other of said inductoriums operative for reversing circuit connections therebetween, a home relay controlling the operation of said means, and a distant relay controlling the operation of the said provisions.
9. In an induction train control system, the combination of sets of parallel inductoriums paralleling the trackway, one set for each section or block of the track, a roadside source of energy for said inductoriums, means connecting an inductorium of one set to said source of energy operative for breaking circuit connections therebetween, provisions for connecting the other inductorium of a set to said source of energy operative for reversing circuit connections therebetween, home and distant relays for each set, the home relay controlling the operation of the said means and the distant relay controlling the operation of the said provisions, and circuit means for controlling the distant relay of one set from the home relay of another set.
10. In an inductive train control system, the combination with the track rails subdivided into a plurality of sections or blocks, of roadside mechanism comprising a plurality of inductoriums for each section or block, a roadside source of energy, and roadside means connecting said source of energy to said inductoriums operable in response to track conditions for reversing the direction of flow of current in one inductorium relative to the other and for discontinuing the flow of current in one of said inductoriums under predetermined conditions.
11. In an inductive train control system, the combination with track rails subdivided into a plurality of sections or blocks, of roadside mechanism comprising a plurality of inductoriums for each section or block, a roadside source of energy, and means connecting said source of energy to said inductoriums including provisions for reversing circuit connections to one of said inductoriums and provisions for breaking circuit connections to one of said inductoriums in response to track conditions.
12. In an inductive train control system, in combination, a plurality of roadside inductoriums, a roadside source of energy therefor, a home relay and a distant relay, and circuit connections between said source of energy and said inductoriums controlled by said relays.
13. In an inductive train control system, in combination, sets of inductoriums, a plurality in each set, a roadside source of en-

- avg for said inductoriums, a home relay and a distant relay for each set of inductoriums, the distant relay of one set being controlled by the home relay of another set, and circuit connections between said source of energy and said inductoriums controlled by both said relays of a given set.
14. In an induction train control system, in combination, a plurality of roadside inductoriums, a roadside source of energy, means for connecting said source of energy to one of said inductoriums operative for breaking circuit connections therebetween, provisions for connecting said source of energy to the other of said inductoriums operative for reversing circuit connections therebetween, a home relay controlling the operation of said means, and a distant relay controlling the operation of said provisions.
15. In an inductive train control system, the combination with track rails subdivided into a plurality of sections or blocks, of roadside mechanism comprising a plurality of inductoriums for each section or block, a roadside source of energy, and means connecting said source of energy to said inductoriums including provisions for reversing circuit connections to one of said inductoriums and provisions for breaking circuit connections to one of said inductoriums in response to track conditions, home and distant relays for each block, the distant relay controlling the operation of said first mentioned provisions and the home relay controlling the operation of said second mentioned provisions.
16. In combination with track rails subdivided into insulated sections or blocks, train control means, a vehicle carried two element relay for producing selectively different effects in said train control means, a plurality of vehicle inductoriums connected to the elements of said relay, a plurality of cooperating roadside inductoriums for each section or block of the track, a roadside source of energy, and means for selectively energizing said roadside inductoriums from said source of energy.
17. In combination with track rails subdivided into insulated sections or blocks, train control means, a vehicle carried two element relay for producing selectively different effects in said train control means, a pair of vehicle inductoriums one connected to each of the elements of the relay, a plurality of cooperating roadside inductoriums for each section or block of the track, a roadside source of energy, and means for selectively energizing said roadside inductoriums from said source of energy.
18. In a continuous induction train control system in combination with track rails subdivided into insulated sections or blocks, a plurality of parallel inductoriums paralleling the trackway, a roadside source of energy therefor, means for selectively energizing said inductoriums from said source of energy, a plurality of inductoriums carried by a vehicle for cooperation with said roadside inductoriums, a vehicle control means and a two element relay connected to said vehicle inductoriums and operative for producing selectively different effects in said train control means upon the selective energization of said roadside inductoriums.
19. In an induction train control system, in combination with track rails subdivided into insulated sections or blocks, a train control means, a translating device for producing selectively different effects in the train control means, a plurality of vehicle inductoriums connected to differently influence said translating device and operative for producing different effects therein upon altering of the instantaneous polarity of the current in one inductorium relative to that in the other, a plurality of roadside inductoriums for each section or block of the track cooperating with the vehicle inductoriums, a roadside source of energy therefor, and means for connecting the said source of energy to the said roadside inductoriums operative for altering the instantaneous polarity of the current in one of said inductoriums relative to that in the other.
20. In an induction train control system, a train control means, a speed circuit controller, a two element relay, a plurality of vehicle inductoriums connected to the elements of the relay, a plurality of cooperating roadside inductoriums arranged in parallel longitudinally of the road, a roadside source of energy and roadside means for selectively connecting the source of energy to the roadside inductoriums to selectively energize the same for the selective operation of the relay to influence the train control means and to place the latter under the control of the speed controller.
21. In a continuous induction train control system, a train control means, a speed circuit controller, a two element relay active when the currents in the elements are in phase for influencing the train control means and when the currents differ in phase for placing the train control means under the control of the speed controller, a plurality of vehicle inductoriums connected to the relay elements, a plurality of roadside inductoriums arranged in parallel longitudinally of the road, a roadside source of energy, and means for changing circuit connections between said source of energy and the roadside inductoriums to vary the phase relation of the currents therein.
22. In an inductive train control system, the combination with the track rails subdivided into a plurality of sections or blocks, of roadside mechanism comprising a plurality of parallel inductoriums for each section

- or block, a roadside source of energy and roadside means connecting said source of energy to said inductoriums operable in response to track conditions for modifying the circuit connections for reversing the direction of flow of current in one of said inductoriums relative to the other and for discontinuing the flow of current in one of said inductoriums under predetermined conditions.
23. In an inductive train control system, the combination with the track rails subdivided into a plurality of sections or blocks, of roadside mechanism comprising a plurality of parallel inductoriums for each section or block, a roadside source of energy, and roadside means operable in response to roadside conditions for reversing circuit connections from said source of energy to one of said inductoriums, and additional means also operable in response to roadside conditions for breaking circuit connections from said source of energy to one of said inductoriums.
24. In an inductive train control system, the combination with the track rails subdivided into a plurality of sections or blocks, of roadside mechanism comprising a plurality of parallel inductoriums for each section or block, a roadside source of energy, and means for connecting the said source of energy to one of said inductoriums operative to reverse circuit connections therebetween.
25. In an inductive train control system, the combination with the track rails subdivided into a plurality of sections or blocks, of roadside mechanism comprising a plurality of parallel inductoriums for each section or block, a roadside source of energy, and means for connecting the source of energy to one of said inductoriums operative to reverse circuit connections to one of said inductoriums, and means for connecting the source of energy to the inductoriums operative to reverse circuit connections to one of said inductoriums and to break circuit connections to one of said inductoriums, said means comprising a pole changer and a make and break device.
26. In a continuous inductive train control system, the combination with the track rails subdivided into a plurality of sections or blocks, of roadside mechanism comprising a plurality of parallel inductoriums for each section or block, a roadside source of energy, and means for connecting the source of energy to one of said inductoriums operative to reverse circuit connections to one of said inductoriums and to break circuit connections to one of said inductoriums, said means comprising a pole changer and a make and break device.
27. In a continuous inductive train control system, the combination with the track rails subdivided into a plurality of sections or blocks, of roadside mechanism comprising a plurality of parallel inductoriums for each section or block, a roadside source of energy, and means for connecting the source of energy to the inductoriums operative to reverse circuit connections to one of said inductoriums and to break circuit connections to one of said inductoriums, the said means comprising a pole changer and a make and break device.

In testimony whereof I affix my signature.
ARCHIBALD G. SHAVER.
